UNITED STATES PATENT OFFICE

2,488,906

VELOCITY-MODULATED ELECTRON-
DISCHARGE DEVICEBernard C. Gardner, Waltham, Mass., assignor to
Raytheon Manufacturing Company, Newton,
Mass., a corporation of Delaware

Application October 31, 1945, Serial No. 625,732

1 Claim. (Cl. 315—5)

1 This invention relates to electron-discharge devices, and more particularly to electron-discharge devices of the velocity-modulated types known as Klystrons and reflex Klystrons.

In certain instances, the tuned circuits, generally, cavity resonators, with which tubes of this character are commonly associated are integral with the equipment in which they are employed, and when such tubes become inoperative, it is necessary, in replacing the same, most accurately to fit the new tubes to the resonators. This is extremely difficult of performance, especially when operating in the field.

Furthermore, the lack of a permanent connection between the tube and the cavity resonator gives rise to oxidation and other impairment of the junction therebetween which results in poor electrical continuity.

It is, therefore, an object of the present invention to provide an electron-discharge device of the Klystron or reflex Klystron type in which the tube is permanently associated with the cavity resonator so that replacement may be effected merely by removing the spoiled tube from its socket and substituting a new one therefor.

It is a further object of the present invention to provide an electron-discharge device of the general character indicated which includes, as an integral part of the cavity resonator thereof, a heat-radiating and tube-protecting shell surrounding said tube.

These, and other objects of the present invention, which will become more apparent as the detailed description thereof progresses, are attained, briefly, in the following manner:

An evacuated, dielectric envelope is provided to enclose an electron gun, a pair of grids spaced from said gun, and a repeller electrode spaced from said grids. Said grids are sealed through the walls of the envelope and are connected, respectively, to the terminals of a tuned circuit. Said tuned circuit consists of a cavity resonator which is integrally formed at one end of a conducting shell, the other end of which is supported on a base member. The arrangement is such that the tube itself is suspended within the shell in spaced relationship to the base member.

In the accompanying specification there is described, and in the annexed drawing shown, an illustrative embodiment of the electron-discharge device of the present invention. It is, however, to be clearly understood that the present invention is not to be limited to the details herein shown and described for purposes of illustration only, inasmuch as changes therein may be made without

the exercise of invention, and within the true spirit and scope of the claims hereto appended.

In said drawing, the single figure is a partial side elevational, partial vertical sectional view of a velocity-modulated electron-discharge device made in accordance with the principles of the present invention.

Referring now more in detail to the aforesaid illustrative embodiment of the present invention, 10 with particular reference to the drawing illustrating the same, the numeral 10 generally designates a velocity-modulated electron-discharge device of the type known as a reflex Klystron.

Said device comprises an evacuated glass envelope 11 having a reentrant press 12 formed at one end thereof from which there is supported an electron gun, said gun consisting, for example, of a suitably coated cathode 13, which is adapted to be heated by a filament 14 to a temperature of 20 thermionic emission, surrounded by an accelerating electrode 15.

Spaced from said electron gun is a pair of grids 16 and 17, said grids being supported as by having portions 18 and 19 thereof sealed through the 25 walls of the envelope 11 and provided, at their outer edges, respectively, with outwardly-directed flanges 18' and 19'.

Spaced from said grids 16 and 17 is a repeller electrode 20 which may be supported, for example, at the end of a lead-in conductor 21 sealed 30 through the envelope 11 at the end thereof opposite the press 12.

Surrounding the tube thus far described is a 35 conducting shell, made, preferably, of a nickel-steel alloy having approximately the same temperature coefficient of expansion as the glass envelope 11, and consisting of a cylindrical heat-radiating and tube-housing portion 22 and an integrally formed toroidal cavity resonator 23. The 40 cavity resonator 23 has its edges soldered or otherwise permanently secured, respectively, to the flanges 18' and 19' of the external portions 18 and 19 of the grids 16 and 17, and the housing portion 22 is crimped at its lower end, as at 24, to a base member 25, the arrangement being such that the tube portion of the device is supported in 45 spaced relationship to said base member.

The cavity resonator 23 is provided with one or 50 more threaded, tubular extensions 26 receptive of adjustable plugs 27 carrying, at their inner ends, tuning members 28, said tuning members extending into said cavity resonator to tune the same in a manner well known to those skilled in the art.

The cavity resonator is also provided with a tubular extension 29 which, together with a cou-

pling loop 30, may be connected to a transmission line to convey power from the device.

This completes the description of the aforesaid illustrative embodiment of the electron-discharge device of the present invention. It will be noted that said device incorporates, as a permanent part thereof, a tuned circuit in the form of a cavity resonator, and thereby eliminates the disadvantages of the prior art referred to in earlier portions of this specification. It will be further noted that said device includes a heat-radiating and tube-protecting shell which renders the same more rugged than devices of the prior art.

Other objects and advantages of the present invention will readily occur to those skilled in the art to which the same relates.

What is claimed is:

An electron-discharge device comprising: a dielectric envelope; a plurality of electrodes including an electron gun, a pair of grids, and a repeller electrode enclosed in said envelope; said grids having annular flanges formed therewith and sealed through the walls of said envelope; a base member for mounting said device in a socket; said

5 base member having external contact prongs connected through said envelope to at least some of said electrodes; and a cylindrical shell surrounding said envelope and, at one end thereof, forming a toroidal cavity resonator with said annular flanges; said shell having its other end sealed to said base member and supporting said envelope in spaced relationship to said base member.

10
